UNITED STATES PATENT OFFICE.

EDWARD RATHBUN, OF TOLEDO, OHIO.

ENGINE.

1,079,440.

Specification of Letters Patent.

Patented Nov. 25, 1913.

Application filed May 29, 1908. Serial No. 435,779.

To all whom it may concern:

Be it known that I, EDWARD RATHBUN, a citizen of the United States of America, and a resident of Toledo, county of Lucas, and State of Ohio, have invented certain new and useful Improvements in Engines, of which the following is a specification.

My invention relates to the jackets of gas engines and other engines requiring cooling of their cylinders, and comprises head jackets and cylinder jackets connected to receive the cooling fluid successively, as hereinafter described.

In the water cooling of the cylinders of large gas engines and the like, having both cylinder jackets and head jackets, (which are usually directly connected), considerable difficulty is experienced from too high temperature of the water in the head jacket.

While the cylinder head is the hottest part of the cylinder, the connections of the head jacket and cylinder jacket are usually such that the head jacket receives the cooling water after it has been heated to a considerable degree in the cylinder jacket; so that the water is hottest at the point where it should be coldest. As a result, the cylinder head is maintained at a higher temperature than is desirable, and steam may be liberated in the head jacket and pocketed there.

According to my invention, the head jacket and the cylinder jacket are separate, and receive the cooling water successively, the water being admitted first to the head jacket, and passing thence to the lower portion of the cylinder jacket, flowing up through the latter and finally passing out at or near the top of the cylinder jacket.

The objects of my invention, therefore, are to cool gas engine cylinders and the like more efficiently, to supply the coldest water to the part near which the highest temperature is produced, and to avoid complications.

I will now proceed to describe my invention with reference to the accompanying drawing showing a central vertical section of the cylinder and associated parts of a vertical type of gas engine, having head and cylinder jackets arranged and connected in accordance with my invention.

In the drawing, 1 designates the cylinder proper, 2 the cylinder head, 3 the piston, 4 the connecting rod, 5 a water-jacketed valve cage for an exhaust valve 6, 7 an exhaust pipe 8 the water jacket of the cylinder head,

and 9 the water jacket of the cylinder. Each of these jackets has an inlet and an outlet port, and I have shown the outlet port 10 of the head jacket connected by a pipe 11 extending forwardly of the cylinder from said port 10 to the inlet port 12 of the cylinder jacket, which port 12 is located near the bottom of the cylinder jacket. Water enters the head jacket at the inlet port 13, and after flowing through the head jacket passes through port 10 and pipe 11 to the inlet port 12 of the cylinder jacket, and flows up through the cylinder jacket, finally flowing out through the discharge port 14 near the top of said jacket. By this arrangement, the coldest water is in the cylinder head, which is exposed to the highest temperatures, and since the water will still be relatively cold when it leaves the head jacket, there is no opportunity for evaporation in the head jacket and consequent pocketing of steam. Thence the water is delivered to the cylinder jacket. Only the upper portion of the cylinder is exposed to the extremely high temperatures to which the cylinder head is exposed, and the thickness of the cylinder walls is usually ample to conduct heat downward through said walls so that overheating of the cylinder cannot occur so long as there is water in the jacket; a higher temperature of the water in the cylinder jacket being permissible, therefore, than in the head jacket.

In general, water will be circulated positively through the jackets, either by means of a pump, or as a result of the water being discharged at lower pressure than that at which it is received. I do not illustrate such means for positive circulation, as they are well known.

What I claim is:—

1. A jacketed engine cylinder comprising separate head and cylinder jackets, the former above the latter, each such jacket provided with inlet and outlet ports, the inlet port of the cylinder jacket being near the bottom of said cylinder jacket, the outlet port of said cylinder jacket being near the top of said cylinder jacket, said cylinder also provided with a duct connecting the outlet port of the head jacket and the inlet port of the cylinder jacket, whereby water first admitted to the head jacket flows therethrough and thence through the cylinder jacket.

2. A jacketed engine cylinder comprising separate head and cylinder jackets, the

former above the latter, each such jacket provided with inlet and outlet ports, the outlet port of the head jacket being near the top of such head jacket, the inlet port of the cylinder jacket being near the bottom of said cylinder jacket, the outlet port of said cylinder jacket being near the top of said cylinder jacket, said cylinder also provided with a duct connecting the outlet port of the head jacket and the inlet port of the cylinder

jacket, whereby water first admitted to the head jacket flows therethrough and thence through the cylinder jacket.

In testimony whereof I have signed this specification in the presence of two subscribing witnesses.

EDWARD RATHBUN.
